FUEL CONTROL VALVE

Filed June 20, 1929

UNITED STATES PATENT OFFICE

53 FLOYD E. HARRIS, OF FLINT, MICHIGAN, ASSIGNOR TO GENERAL MOTORS CORPORATION, OF DETROIT, MICHIGAN, A CORPORATION OF DELAWARE

FUEL CONTROL VALVE

Application filed June 20, 1929. Serial No. 372,409.

This invention relates particularly to pressure-controlled valve devices suitable for use in, for example, those types of burner apparatus in which fuel and air are supplied under some degree of heat or pressure. In such apparatus there ordinarily are unavoidable fluctuations in the pressure in the supply lines; and, while the burner may be adjusted for a mixture of fuel and air appropriate to definite pressure conditions, variations in the pressures have been liable to cause the mixture to become too rich or too lean. This control apparatus is an improvement upon apparatus shown and claimed in my pending application S. N. 154,481, filed Dec. 13, 1926, and it is designed primarily to insure greater uniformity than was obtainable by said apparatus in the proportioning of the ingredients of a combustible mixture, regardless of considerable fluctuations in the supply line pressures, an oil-supply valve being smoothly and reliably moved toward its closed position by either a rise in pressure in the oil feed line or by a fall in pressure in the air feed line.

The present invention, however, includes a novel valve organization and a novel bellows organization which, although designed and especially suitable for conjoint use are believed to be respectively capable of numerous alternative uses.

Other objects of this invention, including various details of the oil control organization referred to, may be best appreciated from the following description of an illustrative embodiment of a complete fuel control organization including the same, taken in connection with the appended claims and the accompanying drawing.

40 Figure 1 is a somewhat diagrammatic general view, with parts broken away to a substantially median vertical plane.

Figure 2 is a vertical sectional detail view, on an enlarged scale, taken substantially as indicated by the line 2-2 of Figure 1.

45 Figure 3 is a horizontal sectional detail view, taken substantially as indicated by the line 3-3 of Figure 2.

50 Referring first to the general relationship of parts shown in Figure 1, 11 indicates a

portion of a furnace wall provided with an opening 12, through which a jet of flame may be projected from a burner 13, of any preferred design. This burner may be supplied with air through a conduit 14 and with oil through a conduit 15, 15', a needle valve 16 or its equivalent being employed to control the flow of oil into an inner tube 17 of said burner. Where a common pump is employed to supply air to several burners, or the like, the air pressure may naturally vary according to the number of burners or machines in operation at a given time, as also with the viscosity of the air as determined by temperature conditions; and similar or opposite variations may take place in the oil line 15' or its equivalent. The air pipe 14 is accordingly shown as equipped with an air control organization 18, immaterial to the present invention; and, in order to render the delivery of oil, or its equivalent, dependent upon the pressure of the air, or its equivalent, as the air pressure may be transmitted through a side passage or conduit 19, the present disclosure includes a control organization 20, to which the present invention is, in fact, restricted.

Referring now to Figures 2 and 3, a preferred valve organization is shown as comprising a valve seat element 21, generally cylindrical in form and including a lateral opening 22, which may be in constant communication with the oil pipe 15'; and the flow of oil through the opening 22 may be dependent upon the relative position therein of a tubular valve element 23. This is shown as provided with a longitudinal passage 24 and with a transverse opening or openings 25, positioned between annular collars on said valve element; and it is adapted to be longitudinally shifted, relatively to the opening 22 in the valve seat, by means such as a rod 26.

The passage 24 is shown as opening at its outlet end 27, opposite the attachment of the rod 26, into communication with the pipe 15; and, in case the rod 26 is to be manipulated in accordance with a pressure differential, the passage 24 may inwardly communicate with an additional lateral opening or openings 28,

28',—admitting oil pressure into a variable-volume chamber 29, or the like. In the region of the opening or openings 25 (shown as provided by a transverse boring of the tubular valve element 23) there is shown a peripheral groove or channel 30, preferably corresponding in diameter thereto and/or to the diameter of the valve seat opening 22; and the tubular valve element 23 is also shown as 10 provided with separate series of annular collars 31 surrounding the same both above and below the opening or openings 25,—said collars being separated by additional and comparatively narrow grooves 32 in such manner 15 as to function somewhat similarly to rings upon a piston and to assure against leakage, in either direction, externally of said valve element. The mentioned grooves also tend to obviate sticking and to assure proper guidance of the valve element; and it will be seen that the described construction assures a substantial balance of longitudinal pressures,—practically eliminating any tendency to "react" or "drag" or "flutter" on the part of the 20 valve element and enabling the same reliably to respond to the movements of the rod 26, or its equivalent.

For uses such as those herein more particularly referred to, the variable-volume chamber 29, adapted to receive oil, and an additional variable-volume chamber 33, may be respectively provided by means such as a metallic bellows 34 and a fabric bellows 35,—the latter being shown as of larger diameter. 30 These bellows may be respectively secured to a fixed bellows-carrying smaller plate 36 (within which the valve element 21 may be seated) and to a larger fixed plate 37,—a floating intermediate wall 39 being common to the 35 two bellows although having a lesser area of exposure within the bellows 34 than within the bellows 35. The plates 36 and 37 are shown as rigidly retained in parallelism and in their desired spaced relationship by means 40 of a housing element 40.

The floating intermediate wall 39 may advantageously take the form of a composite flat plate comprising an impervious and entire upper element 41, a stiffening plate 42 and 50 a lesser bellows attachment plate 43,—the latter being shown as apertured to receive the rod 26, retained by means of nuts 44, 45; and the stiffening plate 42 may, if desired, be provided with guide elements 46. These are 55 shown as extending through openings 47 in the housing 40, and either these guide openings or additional openings 48 may be adapted to permit free access of air, within said housing, to the exteriors of said bellows. The 60 fixed bellows-carrying plate 36 is shown as provided with a threaded boss 49, for use in connecting pipe 15' thereto, conditionally to admit oil through the valve seat element 21; and larger bellows-carrying plate 37, shown 65 as cooperating with the housing 40 in the re-

tention of bellows 35, may be provided with stops 50, limiting the collapsing movement of said bellows, and/or with a conduit 51, for the attachment of a gauge or the like, not shown.

Any annular passage provided at 52 in valve seat 21 preferably corresponds in longitudinal extent with the diameter of openings 22 and 25; "flats" suggested at 53 and 54 are optional; and although the described valve organization might be subject to remote control by other means, and although the pressure-responsive organization comprising floating plate 39, by which the rod 26 is manipulable, might be employed for various uses, in the described construction and assembly, the plate 39 being subjected to the opposite pressures of the respective fluids to which its unequal surfaces are exposed, and the valve element 23 being easily movable in either longitudinal direction, the sensitivity of the described oil control organization is favorable to a very exact regulation of the feed of air and oil to the separate burner 13 or its equivalent. Since regulation of the pressure of the air thus ordinarily assures corresponding regulation of the rate of oil feed, it will be understood that relative areas of the movable wall which are exposed to opposite pressures are to be standardized with reference to a desired ratio of feed,—the viscosities of the respective fluids being duly considered in effecting such standardization.

Although the foregoing description has included details of but one complete embodiment of the present invention, it should be understood that not only various features thereof might be independently employed but also that numerous modifications might easily be devised—all within the scope of the present invention.

I claim:

1. For use in a system of the general character described, a pressure-responsive unit comprising: oppositely expansible chambers 110 having in common a floating wall; means so admitting fluids to said chambers as to expose said wall to opposing pressures thereof; and motion-imparting means connected with said wall and extending toward a valve element,—said bellows being carried by opposite and substantially parallel plates one of which provides guidance means for said floating wall.

2. A pressure regulator comprising a pair 120 of opposed plates, means for holding said plates in fixed spaced relation with respect to each other, an expansible bellows secured to each of said plates, a floating wall secured to the adjacent ends of said bellows and constituting the sole means for transmitting pressure from one to the other, means for supplying fluid under pressure to the interior of each of said bellows, said means including ports extending through said plates, 125 130

a valve in one of said ports and means connecting said valve and wall to cause the wall to operate the valve, and guide means carried by said wall, said spacing means being provided with guides for receiving said guide means to confine the wall to reciprocating movement only.

3. A pressure regulator comprising a pair of opposed plates of unequal area, a housing connecting said plates and holding them in fixed spaced relation with respect to each other, said housing including a portion of larger cross section for connection with the larger plate and a portion of lesser cross section for connection with the smaller plate and a shoulder connecting said portions, an expansible bellows secured to each of said plates, a floating wall secured to the adjacent ends of each of said bellows and constituting the sole means for transmitting pressure from one to the other, means for supplying fluid under pressure to the interiors of each of said bellows, and guide means including interfitting parts on said wall and shoulder for confining said wall for reciprocating movement only.

4. In a pressure regulator, a pair of bellows provided with opposed closed ends, a spacer between and in engagement with said ends, a frame supporting said bellows, said spacer and frame carrying interfitting guide means confining said spacer to reciprocating movement.

5. In a pressure regulator, a pair of bellows provided with opposed closed ends, a spacer between and in engagement with said ends, said spacer and the end of one of said bellows being apertured, and a valve having an operating portion passing through the aperture in said end and projecting into the aperture in said spacer, and securing means on said portion received in said last-named aperture.

45 In testimony whereof I affix my signature.
FLOYD E. HARRIS.
